UNITED STATES PATENT OFFICE.

CHARLES R. HOLCOMB, OF CHICAGO, ILLINOIS, ASSIGNOR TO HOLCOMB SAFETY GARMENT COMPANY, OF CHICAGO, ILLINOIS, A CORPORATION OF ILLINOIS.

LEGGING.

Application filed October 19, 1925. Serial No. 63,338.

This invention relates to leggings and relates particularly to leggings of the general type which forms the subject matter of U. S. Letters Patent No. 1,220,806, dated Mar. 27, 5 1917, issued to Fred H. Wheeler and myself as joint inventors and patentees.

Leggings of the general type to which my present invention relates are designed primarily for protecting the legs and feet 10 of molders and others working in and around foundries and elsewhere where molten metal is handled.

As is generally well known, persons who work around cupolas, blast furnaces and in 15 foundries, and particularly those engaged in handling molten metal are exposed to serious injury from burns caused by molten metal spilled or thrown upon them, particularly on the lower portions of their legs 20 and feet, it being a common experience that, without adequate protection, molten metal when spilled will fall on their legs and will sometimes run into their shoes, producing very serious burns and injuries.

25 Many different kinds of leggings have been devised to protect workmen from injury by molten metal and the object of the present invention is to provide certain specific improvements in the legging which forms the subject matter of said prior Patent 30 No. 1,220,806, with a view to better protect the wearer from injury by the causes specified.

35 A particular feature of said prior Patent No. 1,220,806, consists of a flap attached to one edge of the legging which is adapted to fold under and overlap the opposite edge of the legging when adjusted to the leg of a wearer. Heretofore this flap has 40 been unsupported excepting by its attachment to the leg proper and it is found in practice that it has a tendency to sag and wrinkle and thus defeat the purpose for which it is intended.

45 One object of the invention is to prevent sagging and wrinkling of said flap when adjusted for use, and in accordance with my present invention, I attain this object by means of a supporting stay secured to 50 and which extends transversely of said flap, preferably at its lower edge, said supporting stay consisting preferably of a piece of flat spring steel curved to conform substantially to the curvature of the leg.

55 The legging of said prior Patent No.

1,220,806 was also objectionable in the respect that it was constructed so that the lower edge of the legging proper terminated somewhat above the top of the counter of the shoe worn by the user of the legging, 60 thus permitting access of molten metal to the shoe of the wearer above the counter, burning away the leather and permitting molten metal to run into the boot or shoe worn by the user with attendant serious injury to him.

Another object of the invention is to provide a legging which preferably comprises a vamp portion adapted to extend over and cover the instep of the user and which is 70 so constructed that it may be adjusted to the leg of the user so that its lower edge will overlap the counter of a boot or shoe worn by the user and will be held securely 75 in such overlapping position.

In accordance with my invention, I attain this object by cutting out the front side of the legging so that it will fit over the instep, the relation being such that the lower edge of the legging will extend a desired distance below the ankle of the wearer, 80 said legging also comprising longitudinal reinforcing stays secured to the cover portion of the legging and comprising stays 85 at its rear edges and lateral sides which extend to the lower edges of said legging.

My invention also comprises the various other features, combinations of features and details of construction hereinafter described 90 and claimed.

In the accompanying drawings, in which my invention is fully illustrated,

Figure 1 is a front view of a legging embodying my invention and improvements.

Figure 2 is a side view thereof.

Figure 3 is a top plan view thereof;

Figure 4 is a view of the legging developed, showing the inner side thereof.

Describing the invention with particular reference to the drawings, my improved legging, designated as a whole A, comprises a leg covering portion made of suitable flexible fire-resisting material, such as asbestos cloth or fireproofed duck or leather, said leg covering portion being proportioned to form a main section, designated a, which forms the leg covering proper, and a flap a' secured to one lateral edge of said main portion a and which, when adjusted to the leg of a wearer, is adapted to overlap and 100 105 110

to be inserted beneath the edge of said main section other than that to which said flap is attached. As shown, the main and flap portions of said legging are formed integral 5 with each other, within the contemplation and scope of my invention, but may equally well consist of separate pieces of material sewed or otherwise secured together.

Attached to the main leg covering portion 10 α of the legging are stiffening stays, preferably made of band spring steel, secured to the leg covering portion of the legging by suitable means, as rivets.

As shown, there are five of said spring 15 stays comprising stays 1 and 2 at the rear edges of the main leg covering portion α of the legging, a front stay 3 and side stays 4 and 5 intermediate said front and rear stays.

As shown, also, the legging is adapted to 20 be attached to the leg of a wearer by upper and lower spring clips 6 and 7, said clips being preferably substantially circular in shape and being riveted or otherwise secured to the supporting stays 1, 2, 3, 4 and 5, the 25 upper clip 6 being secured to the upper ends of said supporting stays and the lower clip 7 to said supporting stays at a considerable distance above their lower edges, leaving portions 8 of the rear and side supporting stays 30 depending below said lower clip.

At its front side, the main leg covering portion α of the legging is cut out on a curved line as shown at 9 to fit over the instep of the wearer, said cut-out portion being 35 so proportioned, that when the legging is adjusted to the leg of the wearer, its lower edge will overlap the counter of a shoe, boot or the like worn by him.

The lower attaching clip 7 is positioned 40 above the highest point of the cut-out portion and the front stiffening stay 3 is proportioned to terminate substantially even with its lower edge.

Preferably, also, a legging embodying my 45 present invention comprises a vamp portion 10, adapted to extend over and cover the instep and top portion of the shoe, if desired, the edges of the cut-out portion 9 of the main leg covering portion α . Said vamp portion 50 10 may be made of the same material as the main leg covering portion α , or any other suitable fire-resisting material.

To effect the object of the invention as it 55 relates to holding the flap α' flat and in adjusted position, a transverse supporting stay 11 is attached to said flap, one point of attachment of said stay being closely adjacent to the line of attachment to said flap to the main leg covering portion α of the legging.

As shown, said stiffening stay consists of a 60 strip of band steel riveted to the lower edge

of the flap portion α' , said stiffening stay being shaped to conform substantially to the shape of the corresponding portion of the lower spring clip 7.

However, I do not desire to limit myself as to the material from which the supporting stay 11 is made, nor the number used, nor the position between the top and bottom of the legging at which it or they are attached 70 to said flap portion, as good results may be realized by the use of one or more supporting stays made of other material and attached to said flap above its lower edge.

Also, I do not desire to limit myself as to 75 the material of which the supporting stays 3, 4 and 5 are made, as any suitable material, as for example fibre board or stiff leather may be substituted with equally good results.

I claim:—

1. A legging comprising a leg covering portion of flexible material proportioned to form a flap at one lateral edge thereof, longitudinal stay members secured to said leg 85 covering portion, comprising stay members at the lateral edges of the leg covering portion proper, means for securing said legging to a leg, and one or more supporting stays applied to the flap portion of said legging. 90

2. A legging as specified in claim 1, in which the stiffening stay for the flap is applied to its lower edge, and is curved.

3. A legging as specified in claim 1, in which the flap stay securing means comprises 95 a point of attachment positioned closely adjacent to the line of attachment of the flap to the main leg covering portion of the legging.

4. A legging comprising a leg covering 100 portion of flexible protective material provided with a cut out at the lower edge of its front portion adapted to fit over the instep of the user and so proportioned that when the legging is adjusted for use the rear portion of its lower edge will overlap the counter of a shoe worn by the user, stays secured to the leg covering portion of the legging, comprising spaced transverse stays made of resilient material and shaped to encircle the 110 leg of the user, the bottom one of which is positioned closely adjacent to the top of said cut out, and longitudinal stays comprising a front stay which terminates at the lower transverse stay, and side and back stays which extend substantially to the lower edge 115 of the legging.

In witness that I claim the foregoing as my invention, I have hereunto affixed my signature this 13 day of October, 1925.

CHARLES R. HOLCOMB.
